UNITED STATES PATENT OFFICE

2,089,556

DEEP WELL PUMP PISTON

James Phillip Jackson, Oklahoma City, Okla.

Application August 23, 1935, Serial No. 37,473

8 Claims. (Cl. 309—33)

This invention relates to deep well pumps and more particularly to pistons therefor.

An object of the present invention is to provide a piston for deep well pumps of the type disclosed in my companion application, Serial Number 748,703, filed October 17, 1934, wherein the piston is employed both as a power piston and a pumping piston, and to provide such a piston which is composed of a plurality of sections detachably connected to hold piston cup leathers firmly and securely in place and permit their ready replacement when their efficiency becomes impaired from wear; and further to install the cup leathers with some of them cupping in one direction and others in the opposite direction.

Another object of the present invention is to provide a piston as specified wherein all of the metallic parts of the piston are smaller in diameter than the cylinder in which it reciprocates, thereby providing relatively large clearances between the piston body and cylinder wall, so that sand or other foreign matter will not cut or score the cylinder walls.

With these and other objects in view, as may appear from the accompanying specification, the invention consists of various features of construction and combination of parts, which will be first described in connection with the accompanying drawings, showing a deep well pump piston of the preferred form embodying the invention, and the features forming the invention will be specifically pointed out in the claims.

In the drawings:

Figure 1 is a side elevation of the improved piston.

Figure 2 is a longitudinal section through the piston with parts broken away.

Figure 3 is an end view of the piston.

Figure 4 is a cross-sectional view of the piston taken on the line 4—4 of Figure 2.

Figure 5 is a cross-sectional view of the piston taken on the line 5—5 of Figure 2.

Figure 6 is a cross-sectional view taken on the line 6—6 of Figure 2.

Figure 7 is a side elevation of a modified form of the improved piston.

Figure 8 is a longitudinal sectional view through the modified form of the piston.

Figure 9 is a cross-sectional view taken on the line 9—9 of Figure 8.

Figure 10 is a cross-section taken on the line 10—10 of Figure 8.

Referring more particularly to the drawings, the improved piston which is particularly designed for use in submerged deep well pumps such as

disclosed in my companion application above referred to, comprises a carrying body 1 to which the piston rod 2 is detachably connected, such as by threaded connection shown at 3. The carrying body 1 has its inner or lower end shaped to form one head, namely the power head 4 of the piston and it has an elongated extension 5 formed thereon extending outwardly and upwardly from the annular shoulder 6. The extension 5 has a threaded stud 7 on its outer end on which the piston head 8 threads. The piston head 8 is held against accidental unthreading movement by the set screw 9.

A plurality of cup leathers 10 are carried by the extension 5. While these members are referred to herein as cup leathers, it is to be understood that this term is employed because such elements in pump constructions are commonly known as cup leathers. They may be constructed of any suitable material, with leather, rubber or any composition found practical without departing from the spirit of the present invention. The inner or lowermost cup leather 10a engages the shoulder 6 and is held tightly thereagainst by the spacer 11a, while the intermediate cup leathers 10b are engaged by suitable combined supporting and spacing members 12. The upper or outermost cup leather 10c is held tightly against the spacer 11c by the inner cup engaging end 14 of the removable piston head 8. The combined supporting and spacing members 12 have substantially cylindrical portions 15 thereon which extend into the interior of the cupped portions of the cup leathers 10 and they have spacing and clamping heads 16 formed thereon which engage against the outer surface of the bottoms of the cup leathers next thereto and clamp them against the ends of the portions 15 of the next combined supporting and spacing member in the piston assembly excepting only that the combined clamping and spacing portion 11a of the lower or innermost member 12 clamps the base of the cup leather 10a against the shoulder 6. The diameter of the larger part of the substantially cylindrical portions 15 is smaller in diameter than the inner diameter of the cup leathers 10 as clearly shown in Figure 2 of the drawings but each of the members 12, the piston head 8 and the piston body 1 have annular abutment surfaces 17 formed thereon against which the inner surfaces of the cup leathers near the edges of the cups engage.

By particular reference to the drawings, it will be noted that the cup leather 10c cups towards the outer or upper end of the piston while the

cup leather 10a cups towards the inner or lower head 4 of the piston. The intermediate cup leathers 10 may all cup towards the head 4 or if it is so desired, a certain number of them inwardly from the head 4 may cup theretowards while the others cup towards the piston head 8.

In pistons for deep well pumps of the type wherein the piston is used as both a power and a pumping piston it has been found highly practical to cup the cup leathers in opposed directions as just specified so as to insure efficient pumping and relatively tight engagement between the piston and bore of the cylinder on both strokes of the piston.

15 Pumps of the type involved in the present invention are used for pumping crude petroleum, water or other fluids from very deep wells and in the large majority of such pumping conditions sand or other foreign matter is at all times present in the fluid pumped. In the present invention the active portions of the piston are in reality the cup leathers, and all of the metallic parts of the piston are of a smaller diameter than the bore of the cylinder 20, in which the piston reciprocates, (see Figure 1 of the drawings), thus providing a relatively great clearance between the metallic parts of the piston and the cylinder wall to prevent cutting or scoring of the cylinder.

Also by making the piston with the metallic parts smaller in diameter than the cylinder bore the wear occasioned by the reciprocation of the piston is taken up by the cup leathers 10. These cup leathers are comparatively inexpensive and with the piston constructed as shown in the drawings and hereinabove described, the leathers may be easily replaced when they have become worn sufficiently to impair their efficient pumping action.

As shown in Figure 2 of the drawings the 40 piston rod 2 extends a relatively great distance into the carrying body of the piston structure and the threaded portion 3 thereof is positioned inwardly from the lower open end of the bore 3a which receives the piston rod. The smooth or 45 unthreaded part of the piston rod 2 outwardly of the threaded part 3 is slightly smaller in diameter than the bore 3a providing a very close clearance between the outer diameter of the piston rod and the bore which, together with the 50 particular positioning of the screw threaded portion eliminates concentration of bending stresses at the root of the thread during operation of the piston..

In Figures 7 to 10 inclusive a modified form of 55 the improved piston is shown, which form is however similar in many respects to the form of piston shown in Figures 1 to 6 inclusive.

In the modified form of the piston the carrying body 30 has an enlarged head 31 formed on its 60 upper end which acts as the pumping head of the piston for pumping the fluid delivered by the pump. Between the piston head 31 and the carrying body 30 is an enlargement 32 which forms a spacer and guide for the uppermost cup leather 65 10c.

The piston of the form shown in Figures 8 to 10 inclusive, like the piston of Figures 1 to 6 includes a plurality of cup leathers 10, the uppermost of which cups towards the upper or pumping end of the piston, while the lowermost cup 10a cups towards the lower or power end of the piston. In the drawings the intermediate cup leathers 10b all cup towards the lower or power end of the piston although some of them may be 75 reversed and cupped towards the pumping end

if it is so desired without departing from the spirit of the present invention.

The various cup leathers 10a, 10b, and 10c are held in their proper position on the carrying body 30 by combined supporting and spacing 5 members 15, while the two uppermost cup leathers are held in proper spaced relation by the spacing collar 11c. The members 15 in the modified construction of the piston are similar in construction to the members 15 of the preferred 10 form of the piston having end portions which clamp against the bases of the various cup leathers and flanges 16 which form spacers between the base of one cup leather and the edge of the other cup leather. The diameter of these 15 flanges or larger portions 16 and of the spacer 11c as well as the piston head 31 are all smaller than the diameter of the bore of the cylinder in which the piston reciprocates, thus providing a relatively great clearance between the metallic 20 parts of the piston and the cylinder wall to prevent cutting or scoring of the cylinder.

The power head or end 33 of the piston of this modified form is formed of a separate piece and is detachably connected, such as by threaded connection 34 with the lower end of the carrying member 30 or with what might be called the reduced extension of the carrying member. The inner end of the member 33 is shaped similarly to the shape of the combined spacing and supporting members 15 and it forms a guiding support for the lowermost cup leather 10a. The member 33 is threaded on the extension or carrying body 30 and serves not only as the power end or head of the piston but as a clamping nut to 35 clamp the various cup leathers 10, spacer 11c and combined supports and spacers 15 in proper position on the carrying body, to form the piston.

The carrying member 30 is provided with an axial bore 35 extending a relatively great distance thereto from its lower end and this bore is threaded inwardly of its lower open end to receive the threaded portion 36 of the piston rod 2. As is clearly shown in Figure 2 of the drawings the threaded portion 36 of the piston rod is so located 45 that when the piston rod is properly connected to the piston the threaded portion will be inwardly a considerable distance from the outer or lower open end of the bore 35 and the piston rod is slightly less in diameter than the diameter of 50 the bore so as to form the very close clearance between these members. The construction of the piston rod and its companion features on the carrying body eliminates concentration of bending stress at the root of the threaded portion 36. 55

If it is so desired, set screws 37 and 38 may be provided for preventing accidental rotation of the piston rod and the member 33 respectively.

It will be understood that the invention is not to be limited to the specific construction or arrangement of parts shown but that they may be widely modified within the invention defined by the claims.

What is claimed is:

1. In a deep well pump piston, a carrying body 65 having one end enlarged to form the pumping head of the piston, a plurality of cup leathers and spacers on said carrying body, and a member forming the power head of the piston threaded on said carrying body and clamping said cup leathers and spacers in position, a piston rod, said carrying body having an axial bore therein extending into the body a distance greatly in excess of the diameter of the piston and having its inner end portion threaded, said piston rod provided 70

- with threads to engage in the threaded portion of said bore.
2. In a deep well pump piston, a carrying body having one end enlarged to form the pumping head of the piston, a plurality of cup leathers and spacers on said carrying body, and a member forming the power head of the piston threaded on said carrying body and clamping said cup leathers and spacers in position, a piston rod, said carrying body having an axial bore therein extending into the body a distance greatly in excess of the diameter of the piston and having its inner end portion threaded, said piston rod provided with threads to engage in the threaded portion of said bore, said threaded portions being inwardly of the open end of the bore, said piston rod outwardly of its threaded portion being slightly smaller in diameter than the diameter of said bore. 5
- 20 3. In a deep well pump piston, a carrying body having an enlargement thereon forming one end of the piston, a piston head detachably carried by said carrying body, a plurality of cup leathers between said detachable head and said enlargement, means carried by said carrying body holding said cup leathers in place, a piston rod, said carrying body having an axial bore therein extending into the body a distance greatly in excess of the diameter of the piston and having its inner 25 end portion threaded, said piston rod provided with threads to engage in the threaded portion of said bore, said threaded portions being inwardly of the open end of the bore and said piston rod outwardly of its threaded portion being slightly 30 smaller in diameter than the diameter of the bore.
4. In a deep well pump piston, a carrying body having one end enlarged to form one head of the piston, a plurality of cup leathers and spacers on said body, a member forming the other head of the piston detachably connected to said body, a piston rod, said carrying body having an axial bore extending thereinto the inner end portion of which bore is threaded, said piston rod provided with threads to engage in the threaded portion 45 of the bore.
5. In a deep well pump piston, a carrying body having one end enlarged to form one head of the piston, a plurality of cup leathers on the body, a member forming the other head of the piston 50 detachably connected to said body, cup leathers at the ends of the piston cupping outwardly towards the piston ends, said carrying body and said head-forming member having portions thereof extending into the end-most cup leathers and 55 engaging portions of the inner surfaces of the cup leathers, a plurality of metallic spacers on said body for holding said cup leathers in proper spaced relation, the maximum diameter of said spacers and of said head-forming member and the enlarged head-forming end of said carrying body being less than the maximum diameter of said cup leathers, a piston rod, said carrying body having an axial bore extending thereinto the inner end portion of which is threaded, said piston rod provided with threads to engage in the threaded portion of the bore. 5
6. In a deep well pump piston, a carrying body having one end enlarged to form one head of the piston, a plurality of cup leathers on the body, a member forming the other head of the piston detachably connected to said body, cup leathers at the ends of the piston cupping outwardly towards the piston ends, said carrying body and said head-forming member having portions thereof extending into the end-most cup leathers and engaging portions of the inner surfaces of the cup leathers, a plurality of metallic spacers on said body for holding said cup leathers in proper spaced relation, the maximum diameter of said spacers and of said head-forming member and the enlarged head-forming end of said carrying body being less than the maximum diameter of said cup leathers, a piston rod, said carrying body having an axial bore extending thereinto the inner end portion of which is threaded, said piston rod provided with threads to engage in the threaded portion of the bore. 10
- 15 7. In a piston for deep well pumps, a carrying body having its upper end enlarged to form a piston head integral with the carrying body, a piston head forming member detachably attached to the bottom or lower end of the carrying body, a plurality of cup leathers and spacers on the body intermediate said heads, said carrying body provided with a piston rod receiving bore extending 20 upwardly thereinto, a piston rod extending into said bore and detachably connected to said body. 25
8. In a piston for deep well pumps, a carrying body having its upper end enlarged to form a piston head integral with the carrying body, a piston head forming member detachably attached to the bottom or lower end of the carrying body, a plurality of cup leathers and spacers on the body intermediate said heads, said carrying body provided with a piston rod receiving bore extending 30 upwardly thereinto, a piston rod extending into said bore and detachably connected to said body, the portion of said piston rod receiving bore near the end of the carrying body being larger 35 in diameter than the diameter of the piston rod. 40
- 45
- 50
- 55
